UNITED STATES PATENT OFFICE

ORIMELL B. OLMSTEAD, OF PULASKI, NEW YORK

STEAM AND HOT WATER BOILER

Application filed May 15, 1929. Serial No. 363,237.

This invention relates to a boiler adapted to supply heat and moisture to any distributing system of corresponding capacity such for example as may be required for house, garages, 5 store and factory heating and also for garment pressing machines and other uses where heat, power and moisture may be required.

The main object is to obtain a rapid conversion of relatively cold water into hot water 10 and steam with a minimum consumption of fuel by causing the water to traverse the combustion chamber through a relatively large number of shallow channels in transit from the cold water inlet to the hot water or steam 15 outlet.

Other objects and uses will be brought out in the following description.

In the drawings:—

Fig. 1 is a perspective view of a boiler 20 embodying the various features of my invention.

Fig. 2 is a perspective view of the detached water-leg with the tubular channels thereon together with the base upon which the water-leg is mounted.

Fig. 3 is a perspective view of the water-leg and base omitting the tubes.

Fig. 4 is an enlarged vertical sectional view taken in the plane of line 4—4, Fig. 1.

30 Figs. 5 and 6 are horizontal sectional views taken in the planes of lines 5—5 and 6—6 respectively, Fig. 4.

As illustrated, this boiler comprises a substantially rectangular horizontal base 1 upon 25 which is mounted an upright rectangular casting forming the four walls 2, 3, 4 and 5 and top wall 6 of a combustion chamber 7.

The base 1, upright wall 2, and top wall 6 are preferably made of cast metal, while 40 the remaining upright walls 3, 4, and 5 are preferably made of sheet metal and heat insulating materials constructed and assembled in the manner hereinafter described to reduce to a minimum the radiation of heat from 45 the combustion chamber to the exterior of the boiler.

The upright wall 2 preferably consists of a hollow rectangular shell of cast steel made in one piece to form, what may be termed, an upright water-leg having a water and steam

chamber 8 having its inclosing walls relatively thin but of uniform thickness to afford a comparatively large capacity for the water and steam.

The base 1 and casing mounted thereon are 55 preferably elongated horizontally in one direction and, therefore, the hollow upright water-leg 2 may be regarded as one of the end walls of the combustion chamber, said water-leg and its chamber 8 being relatively 60 shallow horizontally and extending from side to side and from top to bottom of the boiler to assist in rapid conversion of the cold water into hot water and steam as may be desired.

The outer and inner end walls of the water-leg 2 are connected by integral stays or braces 65 9 arranged at suitably spaced intervals throughout the areas thereof to firmly hold said wall against buckling, while permitting their expansion and contraction without 70 over-straining any of its parts.

The inner end wall of the water-leg 2 is provided with a multiplicity of apertures 10 arranged in vertical spaced parallel horizontal rows throughout the major portion of the 75 area thereof, those of adjacent rows being arranged in staggered horizontal spaced relation for receiving one end of a corresponding number of water-and-steam tubes 11 which extend inwardly from the inner wall 80 of the water-leg 2 across the combustion chamber 7.

That is, the tubes 11 are threaded at one end and screwed into the corresponding thread openings 10 to extend inwardly therefrom lengthwise of and across the combustion chamber to approximately the end wall 3 but in slightly spaced relation thereto to permit endwise expansion of the tubes under varying temperatures.

85 The extreme inner ends of the tubes 11 are closed and are preferably angular or square in cross-section to permit the application of a wrench or similar device thereto for tightening or loosening the tubes in their respective openings 10.

90 The tubes of each row are slightly inclined inwardly and downwardly from the inner wall of the water-leg 2, as shown in Fig. 4, to facilitate the circulation of water and 100

steam therethrough from the interior of the water-leg and return, it being understood that the stays or braces 9 will be arranged out of alignment with the tubes so as to avoid interference with the free circulation of the water and steam through the tubes.

The lower end of the upright water-leg 2 is provided with pendent lugs 12 adapted to overlap upon the inner face of a flange 13 on the adjacent end of the base 1 for receiving clamping bolts 14 by which the water-leg is secured to the base, the lower end face of the remaining portion of the water-leg being substantially flat to rest upon the flat upper face of the base thereby to assist in holding the water-leg in its upright position.

If desired, the lower ends of the upright sides of the water-leg 2 may be provided with aligned clean-out openings 15 to permit any sediment which may accumulate in the bottom of the water-leg to be conveniently removed, said openings being normally closed by plugs 16, Fig. 6.

The remaining upright walls 3, 4 and 5 of the casing may be continuous, as shown in Figs. 5 and 6, except that the wall 4 is provided with a fuel inlet opening 17 for receiving a gas burner 18 or other suitable heater which when installed is adapted to rest upon the upper face of the base 1, as shown in Fig. 4, said burner being provided with an extension 19 projected outwardly through the opening 17 and connected by a pipe 20 to any available source of gas supply which is controlled by valves 21 and 22.

The upright walls 3, 4 and 5 extend from the base 1 to the top wall 6 and are preferably composed of outer and inner U-shaped sheet metal sections 23 and 24 arranged in uniformly spaced relation throughout their areas and receiving between them a filling 25 of asbestos or other suitable heat insulating material.

The ends of the sheet metal section 23 overlap upon the opposite upright sides of the water-leg 2 and are secured thereto by bolts 26 or equivalent fastening means, as shown more clearly in Fig. 5, said overlapping ends being provided with openings for receiving the plugs 16, as shown in Fig. 6.

The lower and upper ends of the outer U-shaped sheet metal section 23 overlap upon the corresponding outer face of the base 1 and top section 6 and are secured thereto by bolts 27 or equivalent fastening means, as shown in Fig. 4.

The opposite ends of the inner U-shaped sheet metal section 24 and also the ends of the U-shaped filler section 25 abut against the inner face of the water-leg 2, as shown in Figs. 5 and 6, and are clamped together at suitable intervals throughout their areas by clamping bolts 28, as shown more clearly in Fig. 5, to form a unitary U-shaped structure which may be clamped to or removed from the

water-leg 2 by simply tightening or loosening the bolts 26 and 27.

It will be observed upon reference to Fig. 4, that the lower and upper ends of the inner U-shaped section 24 and filler 25 respectively abut against the upper face of the base 1 and lower face of the top section 6.

The top section 6 overlaps upon the upper face of the water-leg 2 and is secured thereto by bolts 29 or equivalent fastening means to hold the top section in fixed relation to the water-leg, the remaining portions of the top section being supported by the upright U-shaped sections 23, 24 and 25, said top section being provided with a central outlet 30 to permit the escape of the products of combustion to a suitable flue or stack, not shown.

When the water-leg 2 is secured by the bolts 14 to the base 1, it may be additionally held in an upright position by one or more braces 31 having its lower end bolted or otherwise secured to one side of the base and its upper end firmly secured to the inner face of the water-leg 2, as shown in Fig. 2.

A water supply pipe 32 leading from any available source of supply is connected to the interior of the water-leg 2 near the lower end thereof and is provided with a valve 32' operable at will for controlling the water supply to the boiler.

The water-leg 2 is provided near its upper end with a series of, in this instance, three outlet pipes 34, 35 and 36, one of which, as 34, may be connected to any suitable distributing system for the hot water or steam, the pipe 35 being provided with a safety valve 37, while the pipe 36 is provided with a steam gage 38, the lower end of the water-leg is provided with a blow-off pipe 39 having a valve 39' which when opened permits the sediment and other matter to be blown out to a suitable waste pipe, not shown.

The height of the water in the water-leg 2 may be visually indicated by a water gage 40 having valve connections, 41 and 42 with the interior of the water-leg below and above the water level respectively, the lower valve connection 41 being provided with the usual tricocks.

Operation

If the boiler is to be used for the conversion of water into steam, the valve 32' in the supply pipe 32 will be opened to allow the water to enter the water-leg 2 and water tubes 11 until it reaches a predetermined level sufficient to maintain a steam chamber above the water level whereupon the valve 32' may be closed.

The gas in the burner 18 may then be ignited after opening the valves 21 and 22 to cause the heat developed by the burner to pass upwardly through the combustion chamber thereby causing the heated products of combustion to envelop all the tubes 11, in

transit to the outlet 30, the same time impinging against the inner wall of the water-leg 2 to heat the water therein and also within the tubes 12 and to convert the water into steam which is then delivered through the pipe 34 to the distributing system, not shown.

If the boiler is to be used for hot water circulation, the outlet from the distributing system may be returned to the inlet 32 so that the circulation of the hot water may be substantially continuous.

It will be observed that the tubes 11 are supported entirely by the water-leg 2 and that they are free to expand and contract independently of each other and of the water-leg thereby avoiding any strains upon the joints between the tubes and water-leg.

It will also be observed that each tube may be tightened or loosened independently of the others for repairs or replacements.

Another advantage of the invention is that the water-leg with the tubes thereon may be removed or replaced from and upon the base 1 by simply removing the bolts 14 and disconnecting the brace 31.

A further advantage of the construction described is that the jacket comprising the walls 3, 4 and 5 may be removed and replaced from and upon the base by simply removing the top plate 6 and bolts 26 and 27, the bolts 26 being tapped into thickened portions of the water-leg without completely penetrating the walls of the water-leg.

What I claim is:

In a water-heater, a rectangular base frame, a hollow upright water-leg secured to and rising from the rear side of the base frame and provided with water tubes extending forwardly from the front wall thereof over the base frame, said water leg being closed at its upper and lower ends, lugs depending from the water leg and anchored to the inner face of a side of the base frame, and a diagonal brace connecting the upper portion of the water-leg with another side of the base frame.

In witness whereof I have hereunto set my hand this 2nd day of May, 1929.

ORIMELL B. OLMSTEAD.
